REMOTE CONTROL

Robert Alkan, Locust Valley, N. Y., assignor to
Specialties, Inc.

Application May 26, 1945, Serial No. 595,924

5 Claims. (Cl. 318—31)

1

The present invention relates to remote control apparatus of the type wherein a controlled rotating member at a receiver must follow the continuous or intermittent rotative movements and reversals of a master rotating member at the transmitter, and has for an object to provide a reliable, accurate remote control which will meet the requirements of aircraft use and which can be operated by available direct current of relatively low voltage.

Another object is to provide a remote control giving rotary motion of the follower with high fidelity to both rapid and slow movements of the master rotor.

Still another object is to provide a rotary remote control in which overrunning and hunting are reduced to a minimum.

The nature and objects of the invention will be better understood from a description of a particular, illustrative embodiment for the purposes of which description reference should be had to the accompanying drawings forming a part hereof and in which

Figure 1 is an electrical diagram of an apparatus embodying the invention.

Fig. 2 is a transverse, sectional view of the receiver.

Fig. 3 is a view in elevation showing the contacts and slip rings with the front plate and resistance removed.

Fig. 4 is a perspective view of the resistance unit.

The apparatus comprises a transmitter 5 and a receiver 6 of which the transmitter may be operated by any suitable source as for example, a computer or even by hand and the receiver is actuated by a reversible follow-up motor 7 under control of electrical currents in turn controlled by the transmitter. The transmitter and receiver are of similar construction except that the main shaft 8 of the transmitter can be driven by any suitable mechanism whereas the main shaft 9 of the receiver is arranged to be operated by the follow-up motor. A sensitive, polarized relay 10 controls the electrical circuits to cause the motor to drive in one direction or the other as the rotatable element of the transmitter leads or lags relative to the rotatable element of the receiver.

A description of the receiver shown in Figs. 2, 3 and 4 will serve as a disclosure of the transmitter also. In the electrical diagram similar parts of the transmitter and receiver are marked with the same numbers but the parts of the transmitter are marked with a prime.

2

The shaft 9 mounted centrally in the back plate carries a rotatable member or spider 11 comprising a pair of contact arms 12 and 13 positioned at right angles to each other. The arms carry or terminate in contact elements 14 and 15 respectively, which engage the resistance 16 wound on the front plate to provide a flat resistance unit with a substantially smooth surface presented towards the rotatable spider. The arms 12 and 13 are insulated from each other and are formed at their opposite ends with contacts 18 and 19 engaging respectively pairs of semi-circular contact rings or slip rings 20, 21, 22 and 23 all insulated from each other. The resistance 16 is shown as a flat wound coil but it may be of any construction which provides a circular contact path for the contacts 14 and 15. The resistances are connected to the positive and negative current sources at opposite sides of the circular path of contact so that the voltage is maximum on one side and minimum on the other side with a gradient between. In the particular form of resistance shown, the voltage gradient is uniform along the length of the resistance and the voltage impressed at the contacts during rotation of the spider will vary substantially as the sine and cosine of the angle through which the spider turns. What is more important, however, is the fact that the voltage gradient from one side to the other will be the same in both transmitter and receiver with similar paths of contact which conveniently but not necessarily are circular.

The shaft 9 of the receiver is driven by motor 7 through reduction gearing 25 and 26. The transmitter shaft is controlled in any suitable way to be driven continuously or intermittently in either direction in accordance with the motion to be transmitted.

As shown in the electrical diagram, the follow-up motor is controlled by a sensitive, polarized relay 10 which operates to connect the motor for forward or reverse driving as may be necessary to rotate the spider of the receiver to bring it into synchronism with the spider of the transmitter. The polarized relay includes two principle actuating coils 30 and 31 which for convenience will be termed sine and cosine coils connected to be energized by the circuits which connect the transmitter and receiver elements. In the electrical diagram the spider of the transmitter is shown as turned at an angle α at a given moment during operation from what, for convenience, will be termed as the zero position. The spider of the receiver is at the same instant

turned through a slightly greater angle, $\alpha + \epsilon$, the angle ϵ representing the lead of the transmitter over the receiver. With current applied to the apparatus as indicated the voltage at the contact 14 of the transmitter will be slightly higher than the similar contact 14' of the receiver. Accordingly, current will flow from resistance 16, through the contact arm 12, the semi-circular slip ring 22, the conductor to cosine coil 30, and thence through another conductor to the semi-circular slip ring 22', arm 12', and through the contact 14' to the resistance 16'. This current acting through the cosine coil tends to hold the polarized relay in one position in which the reversing switch is held in the position shown. During rotation of the spider of the receiver to reduce the lead of the transmitter, the current will be reduced until the two spiders are in a position of synchronism and the angle ϵ is reduced to zero. The sine coil 31 is similarly energized by current flowing from the resistance 16, through contact arm 13, semi-circular slip ring 20, the sine coil, slip ring 20', arm 13', to the resistance 16' of the transmitter. The two coils are so arranged that they add their ampere turns to cooperate to actuate the polarized relay in one direction or the other. It will be noted that in each case the operating conductor connected to the slip ring 20 or 22 is also connected to the semi-circular slip ring 21' or 23' of the transmitter but since the contact arms are not in engagement with either of the slip rings of the transmitter, this connection is immaterial. In another position of the spiders, a different set of slip rings will be in operation.

If the polarized relay were actuated only by the sine and cosine coils shown and described, there would be a considerable tendency for the motor to overrun and hunt. In order to avoid this, a third auxiliary coil, (called a differential coil) 33, is provided in the polarized relay and arranged to add algebraically its action to the action of both coils, 30 and 31. Ordinarily, the differential coil opposes the other coils during operation. The differential coil is shown as connected across the terminals of the motor so that as the current in the motor circuit reverses, the current in the differential coil reverses. When the receiver spider approaches a position of synchronism with the spider of the transmitter, the current in the active coils 30 and 31 will be reduced nearly to zero and the differential coil will then act with sufficient power to reverse the polarized relay thereby reversing the motor slightly before the spider of the receiver reaches the position of synchronism. The circuit of the follow-up motor can be adjusted to determine the frequency of reversal of this motor when the two spiders are perfectly synchronized and the motor is merely reversing without turning over a substantial number of turns in either direction. The circuit may be such, for example, that the motor will reverse eighteen times per second.

By analysis of the power in the sine and cosine coils 30 and 31 it will be noted that the voltage in these coils gradually builds up from zero when there is no lead, when the two spiders are in perfect synchronism, to considerable power when there is a substantial lead. The power therefore is approximately proportional to the angle of lead.

In usual operation there is also a difference of power in the sine and cosine coils depending upon the position of the contact arms. When the corresponding arms 12 and 12' of the transmitter

and receiver are in a position of small lead, as near the top of the diagram, Fig. 1, the current in the cosine coil will be low. However, at that time, the current in the sine coil through the arms 13 and 13' will be relatively at its maximum. Accordingly, in usual operation in all positions, the power available for operating the polarized relay is the sum of two electrical currents one of which is relatively high when the other is low and their sum is always sufficient to operate the relay reliably.

It is to be noted that there are positions in which there is no current through one or the other of the sets of arms which work together as when the arm 12 is on one side of the vertical in the electrical diagram and the arm 12' is on the other side of the vertical. This is immaterial because at such time, the other set of arms will be in a position to provide maximum power through the other coil. It is contemplated that at no time will the lead of one spider over the other spider be more than 90° and the follow-up motor is chosen with sufficient power and speed to maintain such operation.

Overrunning is practically eliminated by the circuits shown. As the follower approaches the position of equilibrium, the differential coil is excited by a current proportional to the voltage across the follow-up motor and therefore substantially proportional to its speed wherefore the motor reverses with practically no overrun.

The foregoing description of a particular selected embodiment is illustrative merely and is not intended as defining the limits of the invention. It will be understood that various changes can be made in the structure of parts and the circuit arrangement without departing from the principles of the invention as defined in the appended claims.

I claim:

1. A direct current remote control comprising similar resistances at transmitter and receiver stations respectively, each resistance being formed to provide a circular contact path and adapted to be connected to positive and negative current sources at opposite sides of the circular contact path, at each station a pair of angularly related, rotatably mounted contact arms insulated from each other engaging said resistances, a polarized relay having three coils, an electric motor controlled by the polarized relay connected to drive a pair of arms at the receiver station, an electric circuit connecting the first coil to similar arms of both pairs, a second electric circuit connecting a second coil to the other similar arms, and a third electric circuit connecting the third coil to receive current proportional to, and of the sign of, the voltage across the motor terminals, said first and second coils cooperating as actuating coils to insure actuation of the polarized relay in accordance with the relative positions of the rotatable contact arms at the transmitter and receiver stations and said third coil acting in opposition to the actuating coils to inhibit overrunning of the motor.

2. A direct current remote control comprising similar resistances at transmitter and receiver stations respectively, each resistance being formed to provide a circular contact path and adapted to be connected to positive and negative current sources at opposite sides of the circular contact path, at each station a pair of angularly related, rotatably mounted contact arms insulated from each other, each arm engaging the resistance along said circular path, a revers-

ible follow-up motor connected to a source of constant voltage and arranged to rotate the pair of contact arms at the receiver station continuously or intermittently in either direction, a relay controlling said follow-up motor, said relay having principal actuating coils connected with the contact arms to be energized by current of one sign or the other as the contact arms at the transmitting station move in one direction or the other from a position of synchronism with the contact arms at the receiver station and having an auxiliary actuating coil connected to receive current proportional to and of the sign of the voltage across the motor terminals and arranged to oppose said principal actuating coils and tending to cause reversal of the relay as the contact arms at the receiver station approach a position of synchronism with the arms at the transmitter station.

3. A direct current remote control comprising resistances at the transmitter and receiver stations, a rotatable member at each station having two angularly related contacts engaging the resistances, a reversible follow-up motor arranged to drive the rotatable member at the receiver station intermittently or continuously in either direction, a relay electrically connected to both rotatable members to control the motor in accordance with the relative positions of the rotatable members, said relay including a differential coil connected across the motor terminals tending to cause reversal of the relay when the motor is operating in either direction.

4. A direct current remote control comprising similar, flat wound resistances at transmitter and receiver stations, each resistance being formed to provide a circular contact path and adapted to be connected to positive and negative current sources at opposite sides of the circular contact path, a rotatable member at each station having two angularly related contacts insulated from each other and engageable with the respective resistance along the circular path a reversible follow-up motor connected to drive the rotatable member at the receiver station intermittently or continuously in either direction, a polarized relay controlling said motor having three energizing coils, one electrical circuit connecting one coil and similar contacts of the two rotatable members, a second electrical circuit connecting a second coil and the other set of

similar contacts of the rotatable members and a third circuit connecting the third coil to the motor terminals, said first and second coils being arranged to act to move the relay in the same direction and the third coil being arranged to oppose such movement to prevent overrunning.

5. A direct current remote control comprising similar resistances at the transmitter and receiver stations respectively, each resistance being formed to provide a circular contact path and adapted to be connected to positive and negative current sources, at each station a pair of angularly related rotatably mounted contact arms insulated from each other, each arm engaging the resistance along said circular path, a reversible follow-up motor connected to a source of constant voltage arranged to rotate the pair of contact arms at the receiver station in either direction, a reversing relay controlling said follow-up motor, a polarized relay controlling said reversing relay and having two principal actuating coils connected to receive current from the contact arms to energize the relay in one direction or the other as the contact arms at the receiving stations lead or lag with respect to the contact arms at the transmitter station and having a third coil connected to receive current from across the motor terminals and arranged to act in opposition to said principal coils to cause actuation of the polarized relay and therefore of the reversing relay as the rotatably mounted contact arms at the receiver station approach but before they reach the position of synchronism with the contact arms at the transmitter station.
